[57] CLAIM

The ornamental design for an enclosure for automatic teller machines, as shown.

DESCRIPTION

FIG. 1 is a front view;

FIG. 2 is a top view;

FIG. 3 is a left side view;

FIG. 4 is a right side view;

FIG. 5 is a bottom view;

FIG. 6 is a rear view;

FIG. 7 is a horizontal sectional view; and,

FIG. 8 is a vertical sectional view.

The broken line showing of a teller machine is for illustrative purposes only and forms no part of the claimed design.

FIG. 2

FIG. 3

FIG. 1

FIG. 4

FIG. 5

FIG. 7

FIG. 6

FIG. 8
